FLAGPOLE ENTRY

Theodore F. Schmit, Prospect Heights, Ill., assignor to
Electronic Flag Poles, Inc., Maywood, Ill.

Filed Aug. 20, 1971, Ser. No. 173,739

Term of patent 14 years

Int. Cl. D8—99

U.S. Cl. D8—216

FIG. 1 is a side elevational view of a flagpole entry embodying the ornamental design of the invention;

FIG. 2 is a front elevation thereof, taken substantially from vantage line 2—2 of FIG. 1;

FIG. 3 is a rear elevation thereof, taken substantially from vantage line 3—3 of FIG. 1;

FIG. 4 is a top plan thereof, taken substantially from vantage line 4—4 of FIG. 1;

FIG. 5 is a bottom plan thereof, taken substantially from vantage line 5—5 of FIG. 1; and

FIG. 6 is a cross-sectional view, with parts in elevation taken substantially from vantage line 6—6 of FIG. 2 and looking in the direction of the arrows thereon.

I claim:

The ornamental design for flagpole entry, as shown.
